United States Patent Office

Des. 184,235
Patented Jan. 6, 1959

184,235

CHILD'S VEHICLE

Stuart Nelson Mann, Derby, N. Y., assignor to Evans Products Company, Plymouth, Mich., a corporation of Delaware

Application August 23, 1957, Serial No. 47,488

Term of patent 14 years

(Cl. D34—15)

Fig. 1 is a perspective view of a child's vehicle, embodying my new design;

Fig. 2 is a plan view thereof; and

Fig. 3 is a front elevation thereof.

I claim:

The ornamental design for a child's vehicle, as shown.
